US00D656460S

(12) **United States Design Patent**
Thorsteinsson et al.

(10) **Patent No.:** US D656,460 S
(45) **Date of Patent:** ** Mar. 27, 2012

(54) **ELECTRICAL TRANSFORMER**

(75) Inventors: **Sigurdur Thorsteinsson**, Milan (IT);
Egil Stryken, Solbergelva (NO);
Richard Tinggren, Thalwil (CH)

(73) Assignee: **ABB Technology AG**, Zurich (CH)

(**) Term: **14 Years**

(21) Appl. No.: **29/385,962**

(22) Filed: **Feb. 23, 2011**

CLAIM

The ornamental design for an electrical transformer, as shown and described.

DESCRIPTION

This application is also related to U.S. application Ser. No. 29/275,260, filed Dec. 19, 2006 (now Pat. No. D547,267).

FIG. 1 is a front elevation view of an electrical transformer showing our new design;

FIG. 2 is a top plan view thereof;

FIG. 3 is a left side elevation view thereof; and,

FIG. 4 is a perspective view thereof.
